WARP TENSIONING AND LETTING-OFF
DEVICE FOR WEAVING LOOMSHenry Lakeland, Preston, England, assignor to
Lakeland-Baines Patent Proprietary Company
Limited, Preston, England, a British companyApplication January 3, 1935, Serial No. 295
In Great Britain January 20, 1934

15 Claims. (Cl. 139—100)

The present invention relates to weaving looms, and more particularly to warp tensioning and warp let-off devices for looms.

It is well-known that when weaving with ordinary looms, the tension in the warp is greatest during the shedding and least during the beat-up when all the warps are substantially straight and parallel. Thus the warp is liable to be overstretched during the shedding thereby involving permanent injury thereto and to be allowed to remain over-slack during the beat-up whereby the appearance of the finished cloth may be impaired.

The primary object of the present invention is to provide a compensating motion adapted to maintain the warp at a substantially constant tension throughout all the steps in a weaving operation.

According to the present invention, a weaving loom has a freely angularly displaceable warp beam which is provided with loading means adapted to apply a constant turning moment thereto in one direction.

According to another aspect of the invention, a weaving loom has a freely angularly displaceable warp beam, loading means for applying a turning moment to the warp beam in opposition to the turning moment applied thereto by the warp and means for automatically varying the relative angular disposition of the warp beam and said loading means to maintain substantially constant the effect of said loading means as the warp beam is rotated to let off the warp.

According to a still further aspect of the invention, a weaving loom has a freely angularly displaceable warp beam, means for applying a turning moment to said warp beam from a loading means acting in a given direction to oppose the turning moment applied to the warp beam by the warp and means for automatically varying the angle of connection of said loading means to the warp beam to maintain substantially constant the lever arm of said loading means with respect to the warp beam as the warp beam is rotated to let off the warp. Mechanical means independent of said loading means are provided to positively rotate the warp beam to let off the warp and at the same time to alter the relative angular disposition of the warp beam and said loading means and the connection between the warp beam and the loading means may include a toothed gear mechanism driven from a moving part of the loom to permit change in the relative angular disposition of the warp beam and loading means

without releasing the warp beam from the loading means.

Preferably the warp beam and back carrier are adapted for common angular displacement about a common axis, the said loading means acting commonly upon the loading means and back carrier to apply a turning moment thereto. Furthermore, the rate of positive rotation of the warp beam may be governed by the angular disposition of the warp beam and back carrier. For this purpose the initial position of an actuating element adapted to effect positive rotation of the warp beam and to be periodically displaced into a predetermined terminal position by a moving part of the loom, may be governed by the angular disposition of the warp beam and the back carrier.

Preferably the axis of angular displacement of the warp beam and back carrier is coincident with the axis of rotation of the warp beam.

The invention is more particularly described with reference to the accompanying drawings, in which:—

Figure 1 is a side elevation of the rear part of a loom.

Figure 2 is a corresponding rear view, whilst

Figures 3 and 4 are views of details of the construction.

The warp beam 1 is supported by bearings 2 so as to be freely angularly displaceable; each bearing 2 has a pair of spaced projections 3 for engagement with a slot 4 of a support or bracket member 5 detachably connected to the loom frame 6. The bracket members 5 can be vertically adjusted with relation to the loom frame 6 by virtue of the provision of elongated slots 7 in the loom frame. The bearings 2 can be adjusted upwardly and downwardly by means of adjusting screws 50. A pair of substantially vertically disposed brackets 8 are mounted on the journals 9 of the warp beam, the journals 9 being supported in the bearings 2 and the warp beam being supported from the journals 9 by axially projecting pins or spindles 10.

Each bracket 8 has a bearing element 11 at its upper end for the reception of the ends of the back carrier 12. The bearing elements 11 are adjustable relatively to the brackets 8 whereby the spacing of the back carrier from the warp beam can be adjusted if desired.

The back carrier 12 carries adjacent each end a rotatable toothed wheel 13 each of which meshes with a toothed rim 14 one of which is secured to each end of the warp beam. The toothed wheels 13 are driven through the back carrier 12 by means of a worm wheel 15 meshing with a worm

16 fixedly mounted upon a spindle 17 secured in bearings 18, 19, extending forwardly from the brackets 8. At the lower end of the spindle 17 is secured a ratchet wheel 20 and beneath this a bell-crank lever 21 is freely pivoted on the spindle 17 and bears a pawl 22 which is pressed into engagement with the ratchet wheel 20 by means of a spring 23. A push-rod 24 is pivotally connected to the bell-crank lever 21 through a link 25 having pivots at right-angles to one another to provide a universal joint connection between the push-rod and the bell-crank lever. The push-rod has a collar 26 adjacent one end thereof, and engages through a bearing 27 upon the slay 28 so that the collar 26 is engaged by the bearing 27 during the oscillating movement of the slay to cause displacement of the push-rod into a predetermined terminal position dependent upon the position of the collar 26 upon the push-rod and the amplitude of movement of the slay.

A collar 29 on the push-rod is adapted for engagement by an abutment member 30 formed as a rectilinearly bent rod having an eye 31 at its free end for engagement around the push-rod 24 and pivotally connected to the bracket 8 by means of a pivot bearing 32. A spring 33 engages between the eye 31 of the rod 30 and a collar 34 so as normally to press the push-rod to the right, that is, towards the slay.

30 It will thus be appreciated that the initial position of the push-rod at the commencement of its displacement by abutment of the collar 26 with the bearing 27 will be dependent upon the position of the collar 29 and upon the position of the abutment member 30 with respect to the bracket 8. The position of the abutment member 30 with respect to the bracket 8 can be adjusted by releasing a set pin 35 in the pivot bearing 32, whereby the rod 30 can be displaced to the right or the left and the pin 35 tightened up again.

It will be appreciated that if the rod 30 is displaced to the right the stroke of the push-rod 24 will be increased, whilst if the rod is displaced to the left, the stroke will be decreased.

45 Furthermore, it will be observed that if the brackets 8 are angularly displaced in a clockwise direction as viewed in Figure 1, the rod 30 will move to the right to increase the stroke of the push-rod 24. Thus during the operation of the loom the oscillation of the slay will impart a periodic displacement to the push-rod 24 and periodic angular displacement to the bell-crank lever 21. The amplitude of this displacement during the operation of the loom will depend upon the angular position of the brackets 8, that is on the position of the back carrier 12 so that if for a short period the warp is being taken in more rapidly than it is let off, the brackets 8 and rod 30 will move to the right to cause the rate of let off to be increased.

60 Conversely, if the brackets 8 and rod 30 move to the left the rate of let off will be decreased.

If the teeth of the ratchet wheel are relatively coarse, compared with the periodic angular displacement of the bell-crank lever 21, there will be no angular displacement whatever of the rod 17 corresponding to certain of the strokes of the push-rod 24. A hand wheel 36 is secured at the upper end of the spindle 17 for effecting manual let off of warp.

70 Tension is applied to the warp through the back carrier and warp beam by means of weights 37, suspended by means of chains 38 from quadrants 39 extending rearwardly from the brackets 8. The quadrants are arranged co-axially with the axis

of rotation of the warp beam and the warp beam assembly so that the lever arm of the weights 37 with respect to the warp beam and its assembly will remain constant despite angular displacement of the brackets 8.

5 The warp beam assembly including the brackets 8, back carrier 12, spindle 17 and associated parts, are balanced by balance weights 40 which are adjustably connected to the lower ends of the brackets 8, whereby the angular disposition of the 10 brackets 8 will have no bearing upon the warp tension.

Abutment screws 41 are mounted in threaded lugs 42 extending from the balance weights 40, the abutment screws 41 being adapted for engagement with the frame 6 to limit angular displacement of the brackets 8, in the anti-clockwise direction. A brake consisting of a spring leaf 43 connected to the bracket 8 is provided for preventing over-run of the spindle 17. The warp is 20 indicated by reference numeral 44, and is preferably led off the warp beam to the back carrier in the manner indicated by the dotted line 45.

If desired, however, the warp may be led from the warp beam in the manner indicated by the 25 chain dotted line 46, but in the latter case it will be necessary to employ worm 16 of opposite angle.

One of the chief advantages of the present invention resides in the fact that the tension of the warp is wholly independent of the let-off, the let-off being effected mechanically and independently of the weighting of the warp beam.

Furthermore, the warp beam, in addition to its positive rotation from the gear mechanism driving the same, is freely angularly displaceable in 35 common with the brackets 8 and back carrier 12 under the influence of the loading weights 37 and the warp tension acting in opposite directions. Thus the warp tension is dependent upon the loading weights 37 and is unaffected by the let- 40 off.

50 Thus the warp is maintained under substantially constant tension throughout the whole of each pick that is the tension in the warp is not increased during the shedding and then decreased during the beating up and therefore the warp is not unduly stretched during shedding nor is it allowed to become unduly slack during the beating up so that the beating up can be carried out satisfactorily for all densities of weave.

Again, there is no necessity for any variation in the weighting of the warp, so that a considerable amount of supervision can be dispensed with, and furthermore the fabric is woven quite evenly.

Another advantage lies in the fact that the 55 letting back of the cloth and warp is considerably simplified as this can be carried out simply by reversal of the take-up roller, the tension of the warp being maintained by angular displacement of the warp beam assembly in the anti-clockwise 60 direction, there being no necessity for removal or adjustment of weights.

A further advantage of the invention consists in the fact that a relatively great depth of shedding can be obtained without the application of 65 any undue strain to the warp, and furthermore an increased latitude in the position of the tap-pet for shedding is permissible.

By virtue of the fact that the shedding of the warp imposes no increase in tension upon the 70 warp, the invention is particularly applicable to silk looms.

When the warp is taken from the warp beam in the manner indicated by the dotted line 45 the angle contained by the warp line from the 75

warp beam to the back rest and from the back rest to the heads will vary as the diameter of the warp on the beam is reduced, so that there will be a very slight variation in the warp tension as the weaving proceeds but it is found in practice that this variation is negligible.

If desired, however, this slight variation in the warp tension can be compensated by gradual displacement of the pivot bearing 32 along the bracket 8 so as to vary the average rate of let off as the weaving proceeds, and thus slowly to angularly displace the bracket 8 so as to maintain approximately constant the angle contained between the respective aforesaid warp lines.

In the case when the warp is taken from the warp boom in the manner indicated by the chain dotted line 46, this angular displacement of the bracket 8 can occur automatically to maintain substantially constant the angle contained by the aforesaid warp lines particularly if the number of teeth on the ratchet wheel 20 is sufficiently great to ensure that a displacement of the spindle 17 takes place at every oscillation of the slay.

I declare that what I claim is:—

1. A warp tensioning and let off mechanism for a weaving loom comprising a freely pivoted warp beam, a pair of brackets located one at each end of the warp beam and freely pivoted coaxially with the warp beam, a back carrier extending between and supported by said brackets and adapted to be rotated from a moving part of the loom, a toothed rim at each end of the warp beam, a pair of toothed wheels mounted on the back carrier and engaging with the said toothed rims for rotating the warp beam, and loading means for applying a turning moment to said brackets to oppose the turning moment applied thereto by the warp tension.

2. A warp tensioning and let off mechanism for a weaving loom comprising a freely pivoted warp beam, a pair of brackets freely pivoted coaxially with the warp beam and extending upwardly from their pivotal axis, a back carrier extending between and supported by said brackets, a toothed wheel supported by said brackets and adapted to be driven from a moving part of the loom, a toothed rim on said warp beam engaging with said toothed wheel, and loading means for applying a turning moment to said brackets to oppose the turning moment applied thereto by the warp.

3. A warp tensioning and let off mechanism for a weaving loom comprising a freely pivoted warp beam, a pair of brackets freely pivoted coaxially with the warp beam, a back carrier extending between and supported by said brackets, a toothed wheel supported by said brackets and adapted to be driven from a moving part of the loom, a toothed rim on said warp beam engaging with said toothed wheel, a worm wheel arranged in angularly fixed relationship with said toothed wheel, a spindle supported by and extending longitudinally of one of said brackets, a worm secured on said spindle and engaging said worm wheel, a ratchet wheel secured on said spindle, a lever freely pivoted on said spindle, a pawl pivoted to said lever, a spring on said lever to press the pawl against said ratchet wheel and an actuating member connected with said lever and intermittently displaced by a moving part of the loom to effect rotation of the warp beam, and loading means for applying a turning moment to said brackets to oppose the turning moment applied thereto by the warp.

4. A warp tensioning and let off mechanism for a weaving loom comprising a freely pivoted warp beam, a pair of brackets freely pivoted coaxially with the warp beam, a back carrier extending between and supported by said brackets, a toothed wheel supported by said brackets and adapted to be driven from a moving part of the loom, a toothed rim on said warp beam engaging with said toothed wheel, a worm wheel arranged in angularly fixed relationship with said toothed wheel, a spindle supported by and extending longitudinally of one of said brackets, a worm secured on said spindle and engaging said worm wheel, a ratchet wheel secured on said spindle, a lever freely pivoted on said spindle, a pawl pivoted to said lever, a spring on said lever to press the pawl against said ratchet wheel, and an actuating member connected with said lever and intermittently displaced by a moving part of the loom to effect rotation of the warp beam, the amplitude of movement of said actuating member at each displacement thereof being dependent upon the angular disposition of said brackets and loading means for applying a turning moment to said brackets to oppose the turning moment applied thereto by the warp.

5. A warp tensioning and let off mechanism as claimed in claim 4 comprising a push rod comprising a push rod pivotally connected to said lever, an abutment on said push rod adapted for engagement by the slay of the loom to cause periodic displacement of the push rod into a predetermined final position, resilient means for urging the push rod in a direction towards the slay, a second abutment on said push rod and an abutment member pivoted to one of said brackets and adapted to engage said second abutment in order to adjust the initial position of the push rod in accordance with the angular disposition of the brackets.

6. A warp tensioning and let off mechanism for a weaving loom comprising a freely pivoted warp beam, a pair of brackets freely pivoted coaxially with the warp beam, a back carrier extending between and supported by said brackets, a toothed wheel supported by said brackets, a toothed rim on said warp beam engaging said toothed wheel, loading means for applying a turning moment to said brackets to oppose the turning moment applied thereto by the warp, and actuating means for said toothed wheel including a push rod operatively associated therewith, an abutment on said push rod adapted for engagement by the slay of the loom to cause periodic displacement of the push rod into a predetermined final position, resilient means for urging the push rod in a direction towards the slay, a second abutment on said push rod and an abutment member pivoted to one of said brackets and adapted to engage said second abutment in order to adjust the initial position of the push rod in accordance with the angular disposition of the brackets.

7. A warp tensioning and let off mechanism for a weaving loom comprising a freely pivoted warp beam, a pair of brackets freely pivoted coaxially with the warp beam, a back carrier extending between and supported by said brackets, a toothed wheel supported by said brackets, a toothed rim on said warp beam engaging said toothed wheel, loading means for applying a turning moment to said brackets to oppose the turning moment applied thereto by the warp, a worm wheel arranged in angularly fixed relationship with said toothed wheel, a spindle sup-

ported by and extending longitudinally of one of said brackets, a worm secured on said spindle and engaging said worm wheel, a ratchet wheel secured on said spindle, a lever freely pivoted on said spindle, a pawl pivoted to said lever, a spring on said lever to press the pawl against said ratchet wheel, a push rod pivotally connected to said lever, an abutment on said push rod adapted for engagement by the slay of the loom to cause periodic displacement of the push rod into a predetermined final position, resilient means for urging the push rod in a direction towards the slay, a second abutment on said push rod, and an abutment member pivoted to one of said brackets and adapted to engage said second abutment in order to adjust the initial position of the push rod in accordance with the angular disposition of the brackets.

8. A warp tensioning and let off mechanism for a weaving loom comprising a freely pivoted warp beam, a pair of brackets freely pivoted coaxially with the warp beam, a back carrier extending between and supported by said brackets, a toothed wheel supported by said brackets, a toothed rim on said warp beam engaging said toothed wheel, loading means for applying a turning moment to said brackets to oppose the turning moment applied thereto by the warp, and actuating means for said toothed wheel including a push rod operatively associated therewith, an abutment on said push rod adapted for engagement by the slay of the loom to cause periodic displacement of the push rod into a predetermined final position, resilient means for urging the push rod in a direction towards the slay, a second abutment on said push rod, and an abutment member pivoted to one of said brackets and adapted to engage said second abutment in order to adjust the initial position of the push rod in accordance with the angular disposition of the brackets, said abutment member being adjustable relatively to the bracket supporting it for adjustment of the initial position of the push rod.

9. A warp tensioning and let off mechanism for a weaving loom comprising a freely pivoted warp beam, a pair of brackets freely pivoted coaxially with the warp beam, a back carrier extending between and supported by said brackets, a toothed wheel supported by said brackets, a toothed rim on said warp beam engaging said toothed wheel, loading means for applying a turning moment to said brackets to oppose the turning moment applied thereto by the warp and actuating means for said toothed wheel including a push rod operatively associated therewith, an abutment on said push rod adapted for engagement by the slay of the loom to cause periodic displacement of the push rod into a predetermined final position, resilient means for urging the push rod in a direction towards the slay, a second abutment on said push rod, and an abutment member pivoted to one of said brackets and adapted to engage said second abutment in order to adjust the initial position of the push rod in accordance with the angular disposition of the brackets, said abutment member being adjustable longitudinally of the bracket supporting it to vary its spacing from the pivotal axis of the bracket.

10. A warp tensioning and let off mechanism for a weaving loom comprising a freely pivoted warp beam, a pair of brackets freely pivoted coaxially with the warp beam, a back carrier extending between and supported by said brackets, a toothed wheel supported by said brackets, a toothed rim on said warp beam engaging said

toothed wheel, loading means for applying a turning moment to said brackets to oppose the turning moment applied thereto by the warp and actuating means for said toothed wheel including a push rod operatively associated therewith, an abutment on said push rod adapted for engagement by the slay of the loom to cause periodic displacement of the push rod into a predetermined final position, resilient means for urging the push rod in a direction towards the slay, a second abutment on said push rod, and an abutment member pivoted to one of said brackets and adapted to engage said second abutment in order to adjust the initial position of the push rod in accordance with the angular disposition of the brackets, and means for displacing the pivotal connection of said abutment member to the bracket supporting it in a direction longitudinal of said bracket to afford variation in the spacing of said pivotal connection from the pivotal axis of the bracket.

11. A warp tensioning and let off mechanism for a weaving loom comprising a freely pivoted warp beam, a pair of brackets freely pivoted coaxially with the warp beam, bearings for said warp beam and brackets capable of adjustment to raise or lower the warp beam and said brackets, a back carrier extending between and supported by said brackets, a toothed wheel supported by said brackets and adapted to be driven from a moving part of the loom, a toothed rim on said warp beam engaging with said toothed wheel, and loading means for applying a turning moment to said brackets to oppose the turning moment applied thereto by the warp.

12. A warp tensioning and let off mechanism for a weaving loom comprising a freely pivoted warp beam, a pair of brackets freely pivoted coaxially with the warp beam, a back carrier extending between and supported by said brackets, a toothed wheel supported by said brackets and adapted to be driven from a moving part of the loom, a toothed rim on said warp beam engaging with said toothed wheel, a quadrant extending from at least one of said brackets having a curved boundary concentric with the pivotal axis of the brackets, and a weight suspended from a point on the curved boundary of said quadrant.

13. A warp tensioning and let off mechanism for a weaving loom comprising a freely pivoted warp beam, a pair of brackets freely pivoted coaxially with the warp beam, a back carrier extending between and supported by said brackets, a toothed wheel supported by said brackets and adapted to be driven from a moving part of the loom, a toothed rim on said warp beam engaging with said toothed wheel, balance weights connected to at least one of said brackets, and loading means for applying a turning moment to said brackets to oppose the turning moment applied thereto by the warp.

14. A warp tensioning and let off mechanism for a weaving loom comprising a freely pivoted warp beam, a pair of brackets freely pivoted coaxially with the warp beam, a back carrier extending between and supported by said brackets, a toothed wheel supported by said brackets, a toothed rim on said warp beam engaging said toothed wheel, loading means for applying a turning moment to said brackets to oppose the turning moment applied thereto by the warp, a worm wheel arranged in angularly fixed relationship with said toothed wheel, a spindle supported by and extending longitudinally of one of said brackets, a worm secured on said spindle and

engaging said worm wheel, a ratchet wheel secured on said spindle, a lever freely pivoted on said spindle, a pawl pivoted to said lever, a spring on said lever to press the pawl against said ratchet wheel, a push rod pivotally connected to said lever, an abutment on said push rod adapted for engagement by the slay of the loom to cause periodic displacement of the push rod into a predetermined final position, resilient means for urging the push rod in a direction towards the slay, a second abutment on said push rod and an abutment member pivoted to one of said brackets and adapted to engage said second abutment in order to adjust the initial position of the push rod in accordance with the angular disposition of the brackets, and balance weights connected to said brackets for bringing the centre of gravity of the brackets and the elements which are angu-

larly displaceable therewith substantially into coincidence with the pivotal axis of the brackets.

15. In a weaving loom, the combination of a pivoted warp beam, a pair of pivoted side brackets having their pivotal axes coincident with the axis of said warp beam, said warp beam and said brackets being angularly displaceable under the influence of the warp tension acting in one direction, loading means for angularly displacing said warp beam and said brackets in the opposite direction, a back carrier supported by said brackets and extending therebetween, and a gear mechanism driven from a moving part of the loom and adapted to drive said warp beam, said brackets, back carrier, and gear mechanism being balanced whereby the center of gravity substantially coincides with the pivotal axes of said brackets and said warp beam. 15

HENRY LAKELAND.
